CATALYTIC HYDROCARBON CONVERSION
PROCESS

Ernest W. Thiele, Chicago, Ill., assignor to Standard Oil Company, Chicago, Ill., a corporation of Indiana

Application January 31, 1941, Serial No. 376,766

10 Claims. (Cl. 196—50)

This invention relates to a catalytic hydrocarbon conversion process and apparatus therefore. It pertains more particularly to a fixed bed catalyst system for the production of high octane number motor fuels. The invention is particularly applicable to the isoforming of thermally cracked naphtha but it may also be applied to catalytic cracking, hydrogenation, dehydrogenation, reforming, aromatization, alkylation, gas reversion, etc.

In many catalytic processes employing solid catalysts there is a gradual decrease in catalyst activity from the beginning to the end of each particular run. If low space velocities are employed throughout the run the charging stock may be severely over-treated during the initial period with a resulting formation of excessive amounts of coke, gases and undesirable heavy fractions. If high space velocities are employed throughout the run initial over-treatment may be substantially avoided but the extent of conversion may be too low for practical purposes at the end of a reasonable on-stream period—in other words, the on-stream period would have to be too short from the standpoint of a practical regeneration cycle. A uniform space velocity throughout the conversion part of the cycle results in gradually changing product distribution, an excessively large amount of gas being produced in the initial stage and an excessively small amount of conversion being effected in the final stage of the reaction. This change in product distribution during the course of the run increases the difficulty of product fractionation. A fractionating column designed for the maximum gas and gasoline production cannot be operated efficiently or at designed capacity toward the end of the conversion step. It is impractical to alter, to any appreciable extent, the rate at which charging stock is introduced to such a conversion system because the pumps, heat exchangers, pipe still furnaces, etc. should be designed and operated under fairly constant conditions. An object of my invention is to avoid initial over-treatment and final under-treatment of charging stocks in a fixed bed catalyst conversion system without altering pipe still conditions or charging rates. A further object is to obtain a more desirable product distribution in a catalytic conversion process, i. e., to minimize the formation of gases and other undesirable by-products. In other words, my object is to obtain less coke, less gas and less undesirable heavy polymers per barrel of gasoline produced than has been possible in any prior fixed bed conver-

sion system operating for a similar period of time.

As applied to the isoforming process, the object of my invention is to obtain a product of higher octane number than could be obtained by any prior fixed bed process operated for a similar period of time. The isoforming process comprises the catalytic conversion of thermally cracked naphtha over particular catalysts under such conditions as to obtain a yield of about 95 to 99% and an octane number improvement of about 5 to 15 points, e.g., from about 65 or 70 to about 75 or 80.

When a catalyst first goes on-stream in an isoforming process there is apparently an over-treating since the isoformate initially formed does not have as high an octane number as the isoformate which is obtained after the initial on-stream period. The amount of time required for reaching optimum octane number improvement differs with different space velocities. With high space velocities it may be reached after the first few minutes on-stream, at a space velocity of about 12 v./v./hr. it may be reached at about 18 2 to 6 hours on-stream and at space velocity of 6 v./v./hr. it may be reached at about 6 to 24 hours on-stream. After the optimum octane number improvement has been reached at any space velocity there is a tendency for octane number improvement to fall off with increasing periods of time on-stream. The relationship between octane number improvement and on-stream time at various space velocities is roughly and qualitatively shown in Figure 2.

35 An object of my invention is to provide a method and means for operating an isoforming system at uniform charging rates and pipe still conditions and at a plurality of optimum space velocities whereby maximum octane numbers 40 may be produced throughout a relatively long period of time. Other objects of the invention will become apparent from the following description.

In practicing my invention I employ a plurality of groups of catalyst beds each group comprising a plurality of catalyst beds connected in parallel so that one group of beds may be on-stream while another group of beds is undergoing regeneration. In the on-stream period I first pass the charging stock vapors through one bed of the group, then I discontinue the flow through the first bed and charge the vapors through another bed using in both instances a sufficiently high space velocity to avoid appreciable over-treating. I then divide the charging stock vapors

into parallel streams and pass these streams simultaneously through both beds whereby the space velocity will be half of the space velocity originally employed. Similarly, I may employ each of three beds separately and then pass the vapors through all three in parallel at a third the initial space velocity. Generally speaking, I may use any number of beds in each group and I may pass the charging stock vapors through each each bed or sub-group of beds separately at a relatively high space velocity and then pass the catalyst through more of said beds connected in parallel at relatively lower space velocities so that initial over-treating is substantially eliminated, conversion rates are substantially maintained, losses to gas, coke, etc. are materially reduced, the load on the fractionating system is made more uniform and the quality of the resulting gasoline fractions is increased.

The invention will be more clearly understood from the following detailed description read in connection with the accompanying drawings which form a part of this specification and in which,

Figure 1 is a chart illustrating the principle of my invention as applied to catalytic cracking or other conversion processes;

Figure 2 is a chart illustrating the principle of my invention as applied to isoforming; and

Figure 3 is a diagrammatic flow sheet illustrating a preferred apparatus for practicing my invention.

When gas oil is catalytically cracked over silica-alumina type catalysts at temperatures of about 800 to 1000° F. the percent of conversion to gasoline is dependent upon the space velocities and the on-stream reaction time. Figure 1 is a chart which roughly and qualitatively illustrates how conversion falls off with reaction time on-stream at different space velocities. With percent of conversion plotted on a linear scale and time on-stream plotted on a condensed scale, which more nearly approaches a logarithmic scale, it has been found that the lines of constant space velocity are substantially parallel to each other and that there is an enormous increase in the initial over-treatment from space velocities of about 2 volumes of oil per volume of catalyst space per hour (hereinafter called v./v./hr.) to space velocities of about 0.2 v./v./hr. Thus the conversion obtained at 1.8 v./v./hr. roughly falls along line mm' except that the slight over-cracking in the initial period causes a decomposition of some of the cracked products so that the actual percent conversion line is $p101m'$ instead of $mo1m'$. The cross-sectioned area $mp101$ indicates losses to gas, etc. due to over-treatment.

At a space velocity of 0.9 v./v./hr. the percent conversion will fall along the line nn' but since the converted products will be decomposed due to over-treating in the initial period, the actual gasoline production will fall along the line $p202n'$ and the losses to gas, etc. will be represented by the shaded area $np202$.

At a space velocity of 0.45 v./v./hr. the percent conversion will fall along the line rr' but the actual gasoline production will be along the line $p303r'$, the losses to gas, etc. due to over-treating being represented by shaded area $rp303$. At 0.225 v./v./hr. the percent conversion will be along line ss' , the actual gasoline production will be along the line $p404s'$ and the losses due to over-treating and decomposition in the initial treating period will be represented by shaded area $sp404$. Objects of my invention are to eliminate to the greatest

practical extent the losses to gas, etc. that are represented by the shaded areas hereinabove referred to, to provide a system wherein the conversion to gasoline will be substantially constant and to accomplish these results without appreciably changing the amount or temperature of charging stock vapors in the pipe still transfer line. I accomplish these objects by providing a plurality of catalyst beds connected for individual or parallel flow in a unitary group. Thus assuming that there are eight catalyst beds, A, B, C, D, E, F, G, H, each of one unit volume and that I am charging 1.8 unit volumes of gas oil per hour to the system, I may route the charging stock vapors through the catalyst beds as follows:

Sequence	Catalyst bed	Time on-stream	Space velocity
1	A	10	1.8
2	B	10	1.8
3	C	10	1.8
4	-	10	1.8
5	D	10	1.8
6	-	10	1.8
7	E	10	1.8
8	F	10	1.8
9	G	10	1.8
10	H	20	0.9
11	A+B	20	0.9
12	C+D	20	0.9
13	E+F	20	0.9
14	G+H	20	0.9
15	A+B+C+D	50	0.45
	E+F+G+H	50	0.45
	All chambers	100	0.225

It will be noted from Figure 1 that during the first eight sequences the conversion will be along the lines $p101z_1$ so that there will be negligible over-treating and a conversion to gasoline of about 40%. During the next four sequences the conversion will be along the line $y102x_2$ thereby maintaining substantially the same gasoline conversion but avoiding the over-treating losses represented by area $np3y_1$. During sequences thirteen and fourteen the conversion will be along the line $y203x_3$, again maintaining substantially the same conversion and avoiding the large losses represented by shaded area $rp3y_2$. The final conversion step is along the line $y304x_4$ which maintains substantially the same gasoline conversion and avoids the enormous losses represented by shaded area $sp4y_3$. The total elapsed time will be about six hours which provides ample time for regeneration which, of course, may be effected with all beds connected in parallel. If during this six hours the gas oil had been distributed in parallel over all eight catalyst beds, the overall space velocity would have been 0.225 and the loss to gas, etc. would be that represented by shaded area $sp4y_3$. My invention thus provides a method for eliminating this large loss due to over-treating and for maintaining substantially uniform gasoline conversion throughout the desired on-stream reaction period.

It should be understood, of course, that Figure 1 is diagrammatic and illustrative and that I do not limit myself to any particular number of sequences, any particular space velocities in each sequence or any particular time for effecting conversion in each sequence. These variables will differ with various charging stocks, catalysts and conversion conditions and may be determined by preliminary experiments for each stock and each conversion system. For practical reasons it may be desirable to employ the beds two at a time in the first conversion steps, four at a time in the second, etc. or four at a time in the first conversion steps and all eight in the second step. The

essential feature of the invention is the use of a plurality of catalyst beds which are first operated individually or in sub-groups and thereafter operated in parallel.

General operating conditions for catalytic cracking first in individual beds (or sub-groups) and then in parallel (or groups) are as follows:

	On-stream time		Space velocity	
	Range	Preferred	Range	Preferred
First individual bed	3-30	5-15	0.5-5	1-2
Second individual bed	3-30	5-15	0.5-5	1-2
Both beds in parallel	10-60	20-30	0.25-2.5	0.5-1

By using 12 beds in each of two or more groups I may operate first with the beds connected two at a time, then three at a time, then four at a time. The sequence of steps and general operating conditions for such a catalytic cracking system might be as follows:

Sequence	Catalyst bed	Time on-stream	Space velocity
1	A+B	5-15 min. e. g. 10 min.	1-2 v./v./hr. e. g. 1.8 v./v./hr.
2	C+D	5-15 min. e. g. 10 min.	1-2 v./v./hr. e. g. 1.8 v./v./hr.
3	E+F	5-15 min. e. g. 10 min.	1-2 v./v./hr. e. g. 1.8 v./v./hr.
4	G+H	5-15 min. e. g. 10 min.	1-2 v./v./hr. e. g. 1.8 v./v./hr.
5	I+J	5-15 min. e. g. 10 min.	1-2 v./v./hr. e. g. 1.8 v./v./hr.
6	K+L	5-15 min. e. g. 10 min.	1-2 v./v./hr. e. g. 1.8 v./v./hr.
7	A+B+C	10-20 min. e. g. 15 min.	1-1.6 v./v./hr. e. g. 1.2 v./v./hr.
8	D+E+F	10-20 min. e. g. 15 min.	1-1.6 v./v./hr. e. g. 1.2 v./v./hr.
9	G+H+I	10-20 min. e. g. 15 min.	1-1.6 v./v./hr. e. g. 1.2 v./v./hr.
10	J+K+L	10-20 min. e. g. 15 min.	1-1.6 v./v./hr. e. g. 1.2 v./v./hr.
11	A+B+C+D	15-30 min. e. g. 20 min.	5-1.2 v./v./hr. e. g. .9 v./v./hr.
12	E+F+G+H	15-30 min. e. g. 20 min.	5-1.2 v./v./hr. e. g. .9 v./v./hr.
13	I+J+K+L	15-30 min. e. g. 20 min.	5-1.2 v./v./hr. e. g. .9 v./v./hr.
14	A+B+C+D+E+F	15-30 min. e. g. 20 min.	4-1 v./v./hr. e. g. .6 v./v./hr.
15	G+H+I+J+K+L	15-30 min. e. g. 20 min.	4-1 v./v./hr. e. g. .6 v./v./hr.
16	All 12 beds	15-30 min. e. g. 20 min.	2-8 v./v./hr. e. g. 0.3 v./v./hr.

In the isoforming of thermally cracked naphtha the invention has additional advantages and is even more attractive from a commercial standpoint because of the relatively long periods of on-stream times and the consequent ease of valve changes. Since the yields in isoforming range from about 95 to 98% the losses to gas, etc. due to over-treating will not be as marked as in the case of catalytic cracking but will, nevertheless, be of commercial significance. In isoforming, however, the outstanding advantage of my invention is illustrated by Figure 2 wherein the octane number of the product is plotted against the time on-stream in hours. With a space velocity of 24 v./v./hr. the general shape of the

sub-groups) and then in parallel (or groups) are 40 as follows:

45		On-stream time		Space velocity	
		Range	Preferred	Range	Preferred
First individual bed		1-8	2-4	8-40	12-24
Second individual bed		1-8	2-4	8-40	12-24
Both beds in parallel		2-20	4-16	4-20	6-12

50 If 6 or 12 catalyst beds were employed instead of 8 a more gradual change in space velocities is possible thus with 6 beds the sequence of steps and operating conditions might be as follows:

Sequence	Catalyst bed	Time on-stream	Space velocity
1	A+B	1-4 hrs. e. g. 2 hrs.	8-40 v./v./hr. e. g. 24 v./v./hr.
2	C+D	1-4 hrs. e. g. 2 hrs.	8-40 v./v./hr. e. g. 24 v./v./hr.
3	E+F	1-4 hrs. e. g. 2 hrs.	8-40 v./v./hr. e. g. 24 v./v./hr.
4	A+B+C	2-10 hrs. e. g. 4 hrs.	6-30 v./v./hr. e. g. 16 v./v./hr.
5	D+E+F	2-10 hrs. e. g. 4 hrs.	6-30 v./v./hr. e. g. 16 v./v./hr.
6	All chambers	4-20 hrs. e. g. 6 hrs.	4-20 v./v./hr. e. g. 12 v./v./hr.

octane number curve is represented by zii' . At a space velocity of 12 v./v./hr. the octane number curve is illustrated by line zjj' . At a space velocity of 6 v./v./hr. the octane number curve is illustrated by the line zkk' . The peaks in these curves fall at different times on-stream. An object of my invention is to operate an isoforming system in such a manner as to obtain the benefit of each and all of the octane number peaks. This may be accomplished by employing the eight unit volume bed system hereinabove referred to by charging forty-eight volumes of thermally 76

65 Although the invention is applicable to a wide variety of processes it will be described as applied to isoforming. The charging stock to the isoforming process is a naphtha produced by thermal cracking, preferably of gas oil or heavier hydrocarbons from any source whatsoever. The thermal cracking should preferably be effected at relatively high temperatures and low pressures. Generally speaking, the thermal cracking may be at temperatures of 850 to 1150° F. and it is preferably within the range of about 950 to 1050° F. The pressure may range from

atmospheric to 1000 pounds or more but it is preferably lower than 300 pounds per square inch. The thermal cracking may be on a once-through or recycling basis and the products of the thermal cracking should be fractionated to give an isoforming charging stock with an end point not higher than about 400 to 450° F. The initial boiling point of the isoforming charging stock is of no particular consequence and the stock may include or exclude normally gaseous hydrocarbons. Such charging stock will usually have an octane number of about 65 to 70 and this octane number is increased by the isoforming to a value of about 75 or 80.

Referring to Figure 3, the thermally cracked naphtha is introduced through line 10 and forced by pump 11 through coils 12 of pipe still 13 wherein it is vaporized and heated to give a transfer line temperature of about 800 to 1100, preferably about 925 to 975° F. and a transfer line pressure of about atmospheric to about 50 pounds per square inch, preferably about 10 or 15 pounds per square inch. From transfer line 14 the heated vapors may be passed to any one of a group of catalyst beds but with valve 15 closed and valve 16 open these hot vapors are passed through manifold 17 and one or more of the valved lines 18 to one or more of the catalyst beds, A, B, * * * H. These catalyst beds may be of any desired size and shape, may be in tubular conduits surrounded by heat exchange fluids or arranged in any other manner known to the art but I prefer to employ horizontal catalyst beds about 10 inches to 10 feet, preferably about 2½ feet, in thickness. The incoming vapors are introduced at the top of each bed and withdrawn from the base thereof underneath the screen or catalyst bed support.

The amount of catalyst in each bed will vary with the activity of the particular catalyst and may range from about one-fifth to five times the amount described in this preferred example which is roughly about 500 pounds of catalyst per hundred barrels of stock charged per hour to the pipe still furnace. When all of the stock is charged to beds A and B (valves a, b, aa and bb being open and valves c to h being closed) the space velocity will be about 24 v.v./hr. When it is charged in parallel through beds A, B, C and D (valves a to d and aa to dd being open and valves e to h being closed) the space velocity will be about 12 v.v./hr. When it is charged to all of the beds connected in parallel (all valves a to h and aa to hh being open) the space velocity will be about 6 v.v./hr. I prefer to operate the beds two at a time for two hours, then four at a time for four hours, then eight at a time for eight hours to give a total twenty-four hour on-stream period. Alternatively, I may operate the first four beds in parallel for a two hour period at 24 v.v./hr., then with the next four beds in parallel for a two hour period at 24 v.v./hr. and finally with all eight beds connected in parallel for a two to four hour period at a space velocity of about 12 v.v./hr. thus obtaining an on-stream time of six to eight hours. Other operating sequences will be apparent to those skilled in the art from the above description.

The products of conversion are withdrawn through lines 19 and manifold 20 (valve 21 being open and valves 22 and 37 being closed) and thence discharged through line 23 to a conventional fractionation system which may comprise a fractionating column and one or more stabilizers each provided with conventional reheating

means, reflux means, etc. The gasoline fraction may thus be separated from lighter and heavier hydrocarbons in any conventional manner.

It is undesirable for catalyst beds to remain in contact with charging stock vapors during idle periods and I, therefore, provide a suitable purge gas system. The purge gas such as steam or tall gases from the system may be introduced through line 24, passed through heating coil 25 and discharged to manifold 26 at a temperature which is about the same as or somewhat higher than the reaction temperature. When the charging stock flow is discontinued through beds A and B and transferred to beds C and D, I may open valves a₁ and b₁ in lines 27 to permit purging gas from line 26 to displace the charging stock vapors within beds A and B. Similarly, purging gas is introduced through other lines 27 and valves c₁ to h₁ when the charging stock flow through the corresponding catalyst beds is discontinued. This hot purging gas may also be employed for maintaining the desired temperature in the catalyst beds during idle periods. A relatively small amount of purging gas is required for this purpose and such gas may be separated from the products in the fractionation system.

While beds A to H are on-stream, beds A' to H' are undergoing regeneration preferably while connected in parallel. Flue gas, which may be recycled from the system or produced in a generator or both, is introduced through line 28 and regulated amounts of an oxygen-containing gas, such as air, is introduced through line 29 to form the regeneration gas which may be passed by line 30 to manifold 17' (valve 31 being open and valves 15 and 33 being closed). The catalyst may be regenerated in the conventional manner and the regeneration gases may be removed from the system through line 34, valve 35 being open and valve 22 being closed. The regeneration is preferably effected under a pressure of about 100 pounds per square inch and at such a rate that the maximum temperature will not exceed the safe limits for the particular catalyst which, in the present instance, may be about 1050 to 1100° F. After beds A' to H' have thus been regenerated and purged with flue gas they may go on-stream in the manner hereinabove described for beds A to H. At this time beds A to H will be regenerated by closing valve 31 and introducing the flue gas and air mixture through line 32 to manifold 17, valves 31 and 16 being closed and valve 33 being open. In this part of the cycle the regeneration gases are withdrawn through line 36 while valve 37 is open and valve 21 is closed.

It should be understood that all of the valves may be automatically opened and closed at the desired time intervals by electrical or pneumatic means well known to the art and that the system will thus function continuously to supply a fairly uniform stream to the fractionation system. Over-treating is prevented, full utilization is made of the catalyst over a relatively long period of time and a higher octane number motor fuel or isoformate is produced than could be produced by operating the entire system at any fixed space velocity for a corresponding period of time.

The catalysts employed for isoforming are preferably of the silica-alumina type. Such catalysts may be prepared from acid treated bentonite by making a dough of such bentonite and water, forming pellets, thoroughly drying said pellets and heating them to a temperature of about 850 to 1000° F. Catalyst may also be

prepared by depositing alumina or other metal oxides on or in silica gel. Examples of such other metal oxides are copper, magnesium, beryllium and thorium. Cadmium, titanium, manganese, zirconium, vanadium and cerium have shown slight activity in particular catalysts tested. The catalyst may be prepared by impregnation or by ball milling the metal oxide with silica gel or hydro-gel to form a paste which is subsequently dried and heated to about 850 or 1000° F. Catalysts of the natural or synthetic zeolite type may be employed particularly after sodium is leached out of the catalyst or displaced by aluminum. My invention is not limited to any particular catalyst but is applicable to any solid catalyst which has a tendency to become coated with a carbonaceous deposit during the on-stream part of the cycle and to exhibit a gradual diminishing activity of the type generally illustrated in Figure 1. The catalyst may be in granular or pelleted form. Generally speaking, the same type of catalysts may be employed for catalytic cracking as are employed for isoforming.

When my apparatus is employed for catalytic cracking the chief difference in operation will be a slightly lower temperature, i. e., about 800 to 1000° F., preferably about 900° F., a lower space velocity, preferably ranging from about 2 v.v./hr. for the initial highly active portion of the cycle to about .2 v.v./hr. for the final step when all beds are connected in parallel. The on-stream time in the case of catalytic cracking may employ an initial step of about 5 to 15 minutes, a second step of 10 to 30 minutes, etc. as hereinabove described. Various modifications and equivalent operations will be apparent to those skilled in the art from the above detailed description and my invention is not limited to the specific examples hereinabove set forth except as defined by the following claims.

I claim:

1. In a fixed bed catalytic hydrocarbon conversion system wherein a plurality of catalyst beds are connected for both individual and parallel flow, the method of operation which comprises preheating a charging stock to vaporize it and heat it to conversion temperature, passing the hot vaporized charging stock through at least one of said beds at a sufficiently high space velocity to avoid substantial over-treating and to obtain a desired conversion rate, continuing the treating therein until the catalyst becomes partially deactivated and the desired conversion is no longer obtained at said high space velocity, then discontinuing the flow through said bed and introducing the hot vaporized charging stock into at least one other bed at such high space velocity as to substantially avoid over-treating and to obtain a desired conversion rate, continuing the treating therein until the catalyst becomes partially deactivated and the desired conversion is no longer obtained, and subsequently passing the hot vaporized charging stock in parallel through both beds at a lower space velocity for effectively utilizing the partially deactivated catalyst and maintaining the desired conversion without substantially altering the charging rate to the conversion system or the conditions in the preheating step.

2. The method of claim 1 which includes the further step of passing a hot purging gas through

said first-named bed of catalyst while charging stock flow is discontinued therethrough.

3. In a hydrocarbon conversion system employing a plurality of groups of catalyst beds, each group comprising a plurality of catalyst beds connected in parallel, the method of operation which comprises regenerating one group of catalyst beds while the other group of catalyst beds is on-stream, preheating a charging stock 10 to vaporize it and heat it to conversion temperature passing charging stock vapors through one of the on-stream beds at a high space velocity to obtain desired conversion without substantial over-treating, continuing the treating until said catalyst becomes partially deactivated and the desired conversion is no longer obtained, then transferring the charging stock vapor feed to another on-stream bed, continuing the treating in said other on-stream bed at a high space velocity until the catalyst therein becomes partially deactivated and the desired conversion is no longer obtained, purging reaction vapors from said first bed while the other bed is on-stream, then passing charging stock vapors in 20 parallel through both beds so that the space velocity through the partially spent catalyst beds may be reduced without materially altering the amount of charging stock vapors charged to the group of on-stream catalyst beds and without substantially altering conditions in the pre-heating step.
4. The method of obtaining a desired conversion for a relatively long period of time and for avoiding initial over-treating in catalytic processes employing catalysts having a tendency to become coated with carbonaceous deposits during on-stream reactions and which exhibit a gradual diminishing activity with on-stream time, which method comprises subdividing a 30 conversion zone into a plurality of sub-zones, introducing charging stock vapors to said conversion zone at a substantially constant rate and at a substantially constant temperature, first operating the sub-zones individually until the catalyst therein becomes partially deactivated, and thereafter operating said sub-zones in parallel whereby the space velocity in the sub-zones is reduced by the parallel operation of sub-zones containing partially deactivated catalyst.
5. The method of obtaining a desired conversion for a relatively long period of time and for avoiding initial over-treating in catalytic processes employing catalysts having a tendency to become coated with carbonaceous deposits during on-stream reactions and which exhibit a gradual diminishing activity with on-stream time, which method comprises subdividing a 40 conversion zone into a plurality of sub-zones, introducing charging stock vapors to said conversion zone at a substantially constant rate and at a substantially constant temperature, first operating the sub-zones individually until the catalyst therein becomes partially deactivated, and thereafter operating said sub-zones in parallel whereby the space velocity in the sub-zones is reduced by the parallel operation of sub-zones containing partially deactivated catalyst.
6. The method of obtaining a desired conversion for a relatively long period of time and for avoiding initial over-treating in catalytic processes employing catalysts having a tendency to become coated with carbonaceous deposits during on-stream reactions and which exhibit a gradual diminishing activity with on-stream time, which method comprises subdividing a 50 conversion zone into a plurality of sub-zones, introducing charging stock vapors to said conversion zone at a substantially constant rate and at a substantially constant temperature, passing all of the charging stock through one of said sub-zones in a first initial treating period until the catalyst becomes partially deactivated, then passing all of the incoming charging stock through a second sub-zone until the catalyst becomes partially deactivated in a second initial treating period and thereafter passing charging stock vapors in parallel through both said first and said second sub-zones in a subsequent treating period, the space velocity in the subsequent treating period being substantially lower than the space velocities in the initial treating periods.
- 75 6. The method of claim 5 which includes the

further step of passing a purging gas through the first sub-zone when the flow of charging stock vapors is transferred therefrom to said second sub-zone.

7. The method of claim 5 wherein the conversion is the isoforming of thermally cracked naphtha, wherein conversion temperature is about 800 to 1100° F., and wherein the reaction times and space velocities in the conversion steps are substantially as follows:

	On-stream time	Space velocity
First sub-zone.....	Hours 1-8	V./o./hr. 8-40
Second sub-zone.....	1-8	8-40
Sub-zones in parallel.....	2-20	4-20

8. The method of claim 5 wherein the conversion is the isoforming of thermally cracked naphtha, wherein conversion temperature is about 800 to 1100° F., and wherein the reaction times and space velocities in the conversion steps are substantially as follows:

	On-stream time	Space velocity
First sub-zone.....	Hours About 2- 4	V./o./hr. 12-24
Second sub-zone.....	About 2- 4	12-24
Sub-zones in parallel.....	About 4-16	6-12

9. The method of claim 5 wherein the conversion is catalytic cracking, the temperature of conversion is about 800 to 1000° F. and the on-stream times and space velocities in the 5 treating steps are substantially as follows:

	On-stream time	Space velocity
10	Minutes	V./o./hr.
First sub-zone.....	3-30	0.5 -5
Second sub-zone.....	3-30	0.5 -5
Sub-zones in parallel.....	10-60	0.25-2.5

15 10. The method of claim 5 wherein the conversion is catalytic cracking, the temperature of conversion is about 800 to 100° F. and the on-stream times and space velocities in the treating steps are substantially as follows:

	On-stream time	Space velocity
20	Minutes	V./o./hr.
First sub-zone.....	About 5-15	About 1 -2
Second sub-zone.....	About 5-15	About 1 -2
Sub-zones in parallel.....	About 20-30	About 0.5-1
